UNITED STATES PATENT OFFICE

JENÖ FEJES, OF BUDAPEST, HUNGARY
VALVE-ACTUATING-MECHANISM HOUSING

Application filed July 21, 1927, Serial No. 207,524, and in Great Britain August 7, 1926.

This invention relates to an improved supporting arrangement of the valve controlling gear of internal combustion engines.

It is well known to support the valve gear by a box-like structure arranged above and spaced from the cylinder heads.

The main object of the invention is to provide such a construction that the forces transmitted by each valve and valve controlling member shall be uniformly distributed throughout the whole of the construction.

The invention mainly consists in supporting all the valve controlling members of all the cylinders, with the exception of push rods, tappets and the cams which operate the tappets of the valves, by a hollow box-like member or frame which is separate from the cylinder heads and to which all the supports of the valve gear and guides of the valve stems are secured, the said supports and guides being also attached to the cylinder heads.

The supporting hollow frame may be made of cast or wrought iron, preferably of comparatively thin iron sheeting.

Referring to the accompanying drawings, which illustrate by way of example, one mode of carrying the invention into effect,

Fig. 1 is a transverse section of the improved arrangement along the line A—B of Figure 4,

Fig. 2 is a sectional elevation of a portion thereof along the line C—D in Figure 4,

Fig. 3 is a sectional elevation of a portion of the supporting hollow frame along the line E—F in Figure 4,

Fig. 4 is a plan view of the upper plate of the supporting hollow frame, on a reduced scale as compared with Figures 1—3, and

Figures 5, 6 and 7 are respectively a sectional elevation, an end view and a plan view of one of the rocker shaft supports.

In the drawings *a* is a box-like frame comprising an upper plate *a*₁, a lower plate *a*₂ and a peripheral plate *a*₃ which are secured together by welding as shown at *a*₄. The upper plate *a*₁ is formed with openings *b*₁, *b*₂ for the reception of the inlet and exhaust valve spindle guides, openings *c*₁, *c*₂ for the reception of the guides of the inlet and exhaust valve push rods operating on the rockers *d*

and openings *e* for the reception of supports carrying the spindle on which the rockers are mounted, the plate *a*₁ being formed with flanges surrounding the said openings. The lower plate *a*₂ is similarly formed with corresponding lower openings and flanges surrounding the same.

The box-like frame *a* supports all the valve controlling members, with the exception of the cams which operate the push rods of the valves, viz the spindle *f* which carries the rockers *d*; the push rods *g* for operating the rockers *d* which push rods are guided in *c*₂ and are operated by the exhaust cams mounted in the crank casing; the spring controlled exhaust valve stems *a*₅ guided in *B*₂ and operated by the rockers *d*; the spring controlled inlet valves guided in *B*₁ and the corresponding push rods guided in members mounted in the openings *c*₁. The exhaust valve push rod guides *c*₂ are formed with upper and lower shoulders *c*₃ and *c*₄ abutting against the plates *a*₁ and *a*₂ respectively, the inlet valve push rod guides (not shown on the drawing) being provided with similar shoulders.

As will be seen from Figure 2 the guides *B*₁, *B*₂ of the inlet and outlet valves are secured to the cylinder heads *H* partly by screwing, as indicated at *i*, and partly by edge welding as indicated at *j*, the latter edge welding extending to the cover *k* of the cylinder casing. The said guides *B*₁, *B*₂ as well as the guides of the push rods acting on the rockers are secured to the flanges formed on the plates *a*₁, *a*₂ of the box-like frame *a*, around the corresponding recesses by edge welding as indicated at *l* (see Figures 1 and 2).

The spindle *f* carrying the rockers *d* which are acted upon by the push rods and operate the valves is supported by hollow cylindrical members *m* mounted in the recesses *e* provided in the plates *a*₁, *a*₂ of the box-like supporting frame *a*. The members *m* abut against the under surfaces of the plates *a*₁, *a*₂ by means of annular shoulders *m*₁, *m*₂, being edge-welded to the flanges which project on the outer surfaces of the said plates and surrounding the recesses *e*. The box-like members *m* are provided with a hollow

extension *n* followed by a bearing support *o* for the spindle *f*. Some of the supporting members are provided with means such as indicated at *p*, for the attachment of lubricant receptacles.

5 In Figure 1, I have also indicated a casting *q* which is mounted above the box-like frame *a*, being suitably secured thereto at *r* so as to form a tight enclosure which is filled with lubricating oil. The cover *s* of the casting *q* is suitably held in position such as by means of screw nuts *t* secured to the externally screw threaded part *u* provided at the upper extremity of some of the members *m*.

10 15 Referring to Figures 1 and 2 it will be seen that a heat insulating layer of air *v* is left between the cylinders and the valve controlling mechanism.

I wish it to be understood that the details 20 for carrying the invention into effect may be modified in various respects without in any way departing from the spirit of the invention.

What I claim is:

25 1. A multi-cylinder internal combustion engine comprising in combination with a plurality of cylinders and with the valves, and the valve controlling gear of the engine, a hollow box-like member separate from the heads of the cylinders and supporting substantially the whole of the controlling gear, supports and guides for the valves secured to the said hollow box-like member and to the cylinder heads, so as to space the former from 30 the latter at a distance apart from one another such that a heat insulating layer of air is formed between the box-like member and the cylinder heads, as set forth.

40 45 2. A multi-cylinder internal combustion engine as claimed in claim 1 and in which the said hollow box-like member is made of comparatively thin iron sheeting and the supports and guides of the valves are secured to the box-like member by edge-welding, as set forth.

50 55 3. A multi-cylinder internal combustion engine as claimed in claim 1 and in which the supports and guides of the valves which are secured to the box-like member are secured to the cylinder heads partly by screwing and partly by edge-welding, as set forth.

4. A multi-cylinder internal combustion engine as claimed in claim 1 and in which the valve controlling gear includes rockers and tappets acting on the rockers and the hollow box-like member is made of sheet iron plates and has guides for the said tappets, which guides are edge-welded to the upper and lower plates of the box-like member, as set forth.

5. A multi-cylinder internal combustion engine as claimed in claim 1 and in which the valve controlling gear includes rockers and tappets acting on the rockers and the hollow box-like member is made of sheet iron plates

and has guides edge-welded to the upper and lower plates of the box-like member and annular shoulders lying within the box-like member against the upper and lower plates of the latter, as set forth.

6. A multi-cylinder internal combustion engine as claimed in claim 1 and in which the valve controlling gear includes rockers lying outside the hollow box-like member and the box-like member is made of sheet iron plates in combination with cylindrical members secured to the upper and lower plates of the box-like member and acting as supports for the said rockers, as set forth.

7. A multi-cylinder internal combustion engine as claimed in claim 1 and in which the valve controlling gear includes rockers lying outside the hollow box-like member and the box-like member is made of sheet iron plates in combination with cylindrical members secured by edge-welding to the upper and lower plates of the box-like member and acting as supports for the said rockers, as set forth.

8. A multi-cylinder internal combustion engine as claimed in claim 1 and in which the valve controlling gear includes rockers lying outside the hollow box-like member and the box-like member is made of sheet iron plates in combination with cylindrical members secured by edge-welding to the upper and lower plates of the box-like member and having annular shoulders lying within the box-like member against the upper and lower plates of the latter, as set forth.

In testimony whereof I have signed my name to this specification.

JENÖ FEJES.
